UNITED STATES PATENT OFFICE.

JOSEPH FAUSSE, OF BROCKTON, AND RENÉ E. DUPLESSIS, OF BEVERLY, MASSACHUSETTS, ASSIGNORS TO UNITED SHOE MACHINERY CORPORATION, OF PATERSON, NEW JERSEY, A CORPORATION OF NEW JERSEY.

LASTING MACHINE.

Application filed December 1, 1921. Serial No. 519,130.

To all whom it may concern:

Be it known that we, JOSEPH FAUSSE and RENÉ E. DUPLESSIS, citizens of the United States, residing at Brockton, in the county of Plymouth and State of Massachusetts, and Beverly, in the county of Essex and State of Massachusetts, respectively, have invented certain Improvements in Lasting Machines, of which the following description, in connection with the accompanying drawings, is a specification, like reference characters on the drawings indicating like parts in the several figures.

This invention relates to machines for use in the lasting of boots and shoes. The invention is herein illustrated in its application to means for lasting the toes of shoes, but it will be recognized that in many of its aspects the invention is also applicable to the lasting of other portions of shoes, for example to heel end lasting.

In one important aspect, the invention relates to a type of organization comprising overwiping means and upper clamping means in which the operation of one of said means is dependent upon the operation of the other, for example where a clamping band is applied about an end of a shoe by the action of the wiper operating means. As applied to an organization of this general type, the invention aims to provide for better control than heretofore of the clamping pressure and for greater facility in the operation of the overwiping means. With these and other objects in view, a feature of the invention consists in a novel construction and arrangement of clamp applying and controlling means, the construction shown comprising a cam control for an end embracing band whereby the band is closed about the end of the shoe during a portion of the operative movement of the end embracing wipers and is then maintained in closed position with the clamping pressure substantially unchanged during further movement of the wipers and without substantial resistance to such further wiper movement. The invention thus has important advantages, for example, in its application to a well-known type of McKay toe lasting mechanism wherein the upper is clamped about the toe by a band which is closed as the

wipers are advanced, and in the use of which it is customary to reciprocate the wipers a plurality of times without entirely retracting them from over the bottom of the shoe and then to maintain them in partially closed position for the tacking operation. As applied to such an organization, the present invention permits the repeated movements of the wipers to be effected without variation in the clamping pressure applied about the toe, and without resistance from the clamping means, which is locked in pressure applying position without any tendency to withdraw the wipers from over the shoe bottom. A further advantage is that substantial uniformity is insured in the clamping pressure applied to different shoes of the same size and style.

A further feature of the invention consists in novel means affording provision for adjustment of a shoe end embracing band to conform to different shapes of shoes and to determine the clamping pressure applied in different locations about the end of a shoe. In its embodiment of this feature the construction shown comprises unyielding connections between the ends of the band and the usual band closing slides, with provision for relative adjustment between the slides and the ends of the band in directions lengthwise of the shoe. The band may thus be adjusted to conform to a wide range of shapes including narrow toes and comparatively wide or blunt toes and to apply the required pressure to the corners of the toe irrespective of the shape. As a further provision for conformity to different shapes and sizes, and to determine the pressure applied at the sides of the shoe, the machine herein shown is also provided with means for adjusting the opposite end portions of the band laterally of the shoe.

The above and other features of the invention, together with various details of construction and combinations of parts, will now be more particularly described with reference to the accompanying drawings and pointed out in the claims.

In the drawings:

Fig. 1 is a plan view of toe lasting mechanism in which the invention is embodied;

Fig. 2 shows a portion of the mechanism

of Fig. 1 in side elevation, with parts in section;

Fig. 3 is a section on the line 3—3 of Fig. 2, and

Fig. 4 is a section on the line 4—4 of Fig. 1.

The invention is herein illustrated in its application to a type of bed lasting machine shown and described in greater detail in 10 United States Letters Patent No. 1,284,870, granted on November 12, 1918 upon an application of Matthias Brock, which may be consulted for a better understanding of such features of the general organization of the 15 machine as are not hereinafter described. The machine comprises a support or rest 2 for the toe end portion of shoe materials assembled upon a last the heel end portion of which is mounted upon the usual last pin 20 (not herein shown). For embracing and clamping the upper materials about the toe of the last the machine is provided with a toe band comprising the usual flexible fac- 25 ing 4 and the supporting chain 6. For wiping the upper upwardly about the toe of the shoe and for gathering and wiping its margin inwardly over the bottom of the last, the machine has end embracing wiper plates 8 which are advanced and closed by operat- 30 ing means comprising a rod or plunger 10 and a hand lever 12 connected to said plunger by a link 14. It will be understood that the wipers are first advanced and closed about the toe below the plane of the shoe 35 bottom and are then elevated by treadle means for upwiping the upper about the toe while they are maintained in close engagement with the upper materials by manipulation of the lever 12, such upwiping move- 40 ment being effected by the elevation of the toe lasting head upon which both the wipers and the toe embracing band are supported. After the wipers have been elevated to the overwiping plane they are further ad- 45 vanced and closed by manipulation of the lever 12 to gather and wipe the margin of the upper inwardly over the bottom of the last and to iron down the pleats in the upper material. On McKay shoe work the 50 wipers are moved for a comparatively long distance inwardly from the edge of the shoe bottom, and in accordance with the usual practice they are then partially retracted and again closed inwardly a plurality of 55 times, after which they are positioned with their edges partially retracted to permit the upper fastening tacks to be driven.

The toe embracing band is advanced and closed about the toe of the shoe through 60 closing members or slides 16 which are movable lengthwise of the shoe and are connected to the opposite end portions of the band by mechanism to be more particularly described hereinafter. At their outer ends the 65 slides 16 are pivotally connected to a cross

bar 18 which is in turn connected midway between its opposite ends to a slide 20. Extending from the slide 20 is a stem 22 (Fig. 3) on which is slidably mounted a cross head 24, the stem being provided with a collar 26 to limit the outward movement of the cross-head along the stem. Adjustably threaded in ears 28 on the slide 20, in the construction herein shown, are rods 30 which extend outwardly through the cross head 24 70 and are squared at their outer ends to facilitate their adjustment. Encircling the rods 30 are springs 32 which are partially housed within the cross head 24 and bear at their outer ends on the cross head and at their opposite ends on collars 34 on the rods. 75

Operative movement is imparted yieldingly to the band closing slide 20 through the cross head 24 and the springs 32 by connections which receive their operative move- 80 ment from the wiper operating hand lever 12. For the purposes in view, the wiper operating plunger 10 carries a cam block 36 provided on its opposite sides with path cams 38 in which are mounted rolls 40 car- 85 ried by the upper ends of bell-crank levers 42 mounted on pivots 44 on the toe lasting head. At their lower ends the levers 42 are connected by links 46 to the opposite sides 90 of the cross head 24. It will be understood that the cams, levers and links are duplicated merely for strength and to establish a better balance between the opposite side portions of the mechanism. The path cams 38 are so shaped that as the wiper operating 95 plunger 10 is advanced the bell-crank levers 42 are operated to move the cross head 24 toward the right (Fig. 2) and to impart yieldingly through the springs 32 operative band closing movement to the slide 20. 100 While the cams may be variously shaped to cause the band to be applied in any desired time relation to the movement of the wipers, the construction herein shown is such that the wipers will receive a slight advancing 105 and closing movement relatively to the band, to position their wiping edges in effective engagement with the upper materials for the upwiping operation, before the band receives any substantial closing movement. Immedi- 110ately upon further advancing movement of the wipers, to wipe the upper inwardly over the bottom of the last, the band is closed firmly about the toe by the operation on the levers 42 of portions of the cams which 115 are inclined to the direction of movement of the plunger 10. It will be noted that the lower portions of the cams 38 are substan- 120tially straight and parallel to the direction of movement of the plunger 10. When the rolls 40 arrive in position to engage these lower portions of the cams, the wipers may be further advanced and closed without the application of further pressure to the band. The operator is thus enabled to close the 125 130

wipers inwardly as far as desired to wipe down and compact the marginal portion of the upper materials, and to retract and advance them repeatedly within the limits determined by the lower straight portions of the cams 38, without any variation in the clamping pressure about the toe and while the lever 12 is substantially free from the resistance of the band closing connections, 5 the band being locked in its closed position by the cam and lever mechanism. In practice the wipers will usually be reciprocated thus a plurality of times and then positioned with their edges partially retracted 10 to permit the tacks to be driven while the levers 42 are still under control of the lower straight portions of cams. Thereafter the lever 12 will be further retracted to withdraw the wipers from over the shoe bottom 15 and to effect the opening of the band. 20 The intermediate portion of the toe band is supported and controlled by mechanism substantially as illustrated in Patent No. 1,284,870, whereby the band may be adjusted 25 relatively to the wipers in directions lengthwise of the shoe through the operation of a hand wheel 48, the controlling means also permitting the band to be moved forwardly toward the toe end face of the shoe 30 against the resistance of the usual spring 50 in response to the pull applied at its end portions. The closing slides 16 in their lengthwise movements are wedged toward and from the sides of the shoe to close and 35 to open the band laterally of the shoe by positive means comprising rolls 51 which engage the slides in slots 52 formed in inclined relation to the length of the slides. The connections between the closing slides 16 40 and the ends of the band comprise arms 53 which are mounted on the ends of the slides and are connected by pivots 54 to the ends of the band chain. The arms 53 are slotted horizontally (Fig. 4) to embrace the ends of 45 the slides 16 and are also provided with vertical slots 56 to receive pins 58 which are secured to the ends of the slides. The arms 53 are adjustably positioned with respect to movement laterally of the shoe by means 50 of thumb nuts 60 which are swiveled in the ends of the arms and are threaded on rods 62 the inner ends of which are connected to the pins 58. By turning movements of the nuts 60 the arms may be adjusted inwardly 55 or outwardly, independently of each other, to vary and determine the pressures applied by the end portions of the band at the opposite sides of the shoe. 60 The arms 53 are normally held from turning 65 about the pins 58 by means of rods 64 which are swiveled on pins 66 on the outer ends of the arms and extend through ears 68 on the slides 16. Nuts 70 are swiveled in the ears 68 and are threaded on the ends of the rods 64 for swinging the arms 53 ad- justably about the pins 58 and for maintaining them in adjusted position. Through the adjustable connections thus provided the contour of the band may be varied and adapted to different shapes and sizes of 70 shoes. For example, if the band were to operate upon a shoe having a wider and less pointed toe than that for which it is adjusted in Fig. 1 of the drawings, the rods 75 64 would be operated to swing the pivotal connections 54 between the arms 52 and the ends of the band toward the left, thus permitting the toe end portion of the band to spread out in conformity to the contour of the different shape of toe. To adapt the 80 band for a more pointed toe, the pivotal connections 54 would be swung toward the right (Fig. 1), thus contracting the toe end of the band. It will also be understood that such inward or outward movement of one or both 85 of the arms 53 as may be required by the width and the shape of the toe will be made by turning the nuts 60. In practice a shoe will preferably be mounted in the machine and the band then adjusted to fit the toe 90 and to apply the required degree of pressure in the different locations about the toe, after which substantially the same pressure will be applied on all shoes of the same size and style without the need for further adjustment. 95 It will be evident that the effectiveness of the means provided for adjusting the band to the different shapes of toes and for insuring the required pressure about the corners 100 of the toe is increased by reason of the fact that the connections between the ends of the band and the closing slides 16 are unyielding in the direction of the length of the shoe in the operation of applying the band about 105 the toe. It will also be evident that both the means hereinbefore described for operating the closing slide 20 under predetermined pressure and the character of the connections between this slide and the band contribute to precision in respect to the clamping pressure applied to the shoe. The pressure under which the slide 20 is operated 110 may be varied as desired by adjustment of the compression of the springs 32 through 115 turning movement of the rods 30. It will be evident that such adjustment of these springs is effected without varying the position of the band or the relative positions of the band and the wipers. 120 Having described the invention, what we claim as new and desire to secure by Letters Patent of the United States is: 125

1. In a machine of the class described, the combination with shoe positioning means, of an overlaying wiper, means for operating said wiper to wipe the upper inwardly over the bottom of the shoe, a clamp for engaging the upper on the lateral periphery of the shoe, and mechanism for operating and 130

controlling said clamp by the movement of the wiper operating means to apply the clamp to the shoe during a portion of the inward movement of the wiper and then to maintain the clamping pressure substantially unchanged during further inward movement of the wiper.

2. In a machine of the class described, the combination with shoe positioning means, 10 of an overlaying wiper, means for operating said wiper to wipe the upper inwardly over the bottom of the shoe, a clamp for engaging the upper on the lateral periphery of the shoe, and mechanism controlled by the movement of said wiper operating means for locking said clamp in pressure applying relation to the shoe when the wiper has arrived at a predetermined point in its inward movement and for holding the clamp thus 15 locked during further movement of the wiper beyond said point.

3. In a machine of the class described, the combination with shoe positioning means, of end embracing wipers, means for operating said wipers to wipe the upper inwardly over an end of the shoe and for then partially retracting the wipers to permit the fastening of the upper, a clamp for the end of the shoe, and mechanism automatically 20 controlled by the wiper operating means to apply the clamping pressure to the shoe as the wipers are moved inwardly over the shoe and then to prevent relaxing of the clamping pressure as the wipers are partially retracted.

4. In a machine of the class described, the combination with shoe positioning means, of end embracing wipers, a manually operative member connected to said wipers to advance 40 and close them inwardly over an end of the shoe, a clamp for the end of the shoe, and mechanism for operating said clamp by the movement of said wiper operating member, said mechanism being constructed to apply 45 increasing clamping pressure to the shoe during a portion of the inward movement of the wipers and then to release said operating member from the resistance of said clamping pressure while maintaining said pressure during further inward movement of the wipers.

5. In a machine of the class described, the combination with shoe positioning means, of end embracing wipers for wiping the 55 upper inwardly over an end of the shoe, a clamp for the end of the shoe, a single operating means movable in one direction to advance the wipers and to apply the clamp to the shoe and in the reverse direction to 60 retract the wipers and release the clamp, and connections between said operating means and the clamp constructed to apply the clamping pressure during a partial advance of the wipers and then to maintain 65 the clamping pressure substantially un-

changed during further advance of the wipers.

6. In a machine of the class described, the combination with shoe positioning means, of end embracing wipers for wiping the upper 70 inwardly over an end of the shoe, a clamp for the end of the shoe, a single operating means movable in one direction to advance the wipers and to apply the clamp to the shoe and in the reverse direction to retract 75 the wipers and release the clamp, and mechanism controlled by said operating means for applying the clamping pressure before the wipers have arrived at a predetermined point in their inward movement and for 80 then maintaining said pressure without substantial resistance to movement of said operating means in advancing and retracting the wipers beyond said point.

7. In a machine of the class described, the combination with shoe positioning means, of end embracing wipers, a hand lever for advancing and closing said wipers over an end of the shoe, a clamp for the end of the shoe, and operating connections between said 90 hand lever and the clamp constructed to apply the clamp to the shoe during a portion of the advancing movement of the wipers and then to maintain the clamping pressure substantially unchanged during 95 further advance of the wipers.

8. In a machine of the class described, the combination with shoe positioning means, of end embracing wipers, a hand lever for advancing and closing said wipers over an end 100 of the shoe, a clamp for the end of the shoe, and mechanism controlled by said hand lever for applying the clamp to the shoe during a portion of the advancing movement of the wipers and for locking said clamp 105 in position to apply substantially uniform pressure to the shoe during further advance and partial retracting movement of the wipers.

9. In a machine of the class described, the combination with shoe positioning means, of end embracing wipers, a hand lever for advancing and closing said wipers over an end of the shoe, a band for embracing and clamping the upper about the end of the 115 shoe, and mechanism comprising a cam operated by said hand lever for closing the band about the end of the shoe as the wipers are operated.

10. In a machine of the class described, the combination with shoe positioning means, of end embracing wipers, a hand lever for advancing and closing said wipers over an end of the shoe, a band for embracing and clamping the upper about the 120 end of the shoe, and operating connections between said hand lever and band comprising a cam constructed to close the band about the end of the shoe during a portion 125 of the operative movement of the wipers 130

and then to maintain the band in closed position without substantial change in the clamping pressure during further movement of the wipers.

5. 11. In a machine of the class described, the combination with shoe positioning means, of end embracing wipers, a hand lever for advancing and closing said wipers over an end of the shoe, a band for em-
10 bracing and clamping the upper about the end of the shoe, and mechanism operated by said hand lever for closing the band about the end of the shoe and for controlling the clamping pressure comprising a 15 cam member constructed to lock the band in closed position at a predetermined point in the movement of the wipers and to maintain the band in closed position without substantial resistance to the movement of 20 the wipers as the wipers are further advanced and partially retracted.

12. In a machine of the class described, the combination with shoe positioning means, of an overlaying wiper, operating 25 means for moving said wiper inwardly over the bottom of the shoe, a clamp for engaging the upper on the lateral periphery of the shoe, and operating means for said clamp comprising a cam movable inwardly 30 with the wiper and constructed to apply the clamping pressure to the upper during a portion of the movement of the wiper and then to maintain the clamping pressure sub- 35 substantially unchanged during further inward movement of the wiper.

13. In a machine of the class described, the combination with shoe positioning means, of end embracing wipers, means for operating said wipers, an end embracing band, and operating means for said band comprising a member movable lengthwise 40 of the shoe for closing the band about the end of the shoe and a cam movable lengthwise of the shoe to operate said member.

45. 14. In a machine of the class described, the combination with shoe positioning means, of end embracing wipers, operating means for said wipers comprising a plunger movable lengthwise of the shoe, a band for embracing and clamping the upper about the end of the shoe, and mechanism comprising a cam movable lengthwise of the shoe with said plunger for closing the band about the end of the shoe in predetermined 55 time relation to the wiper movements.

15. In a machine of the class described, the combination with shoe positioning means, of end embracing wipers, operating means for said wipers comprising a plunger 60 movable lengthwise of the shoe, a band for embracing and clamping the upper about the end of the shoe, and mechanism for closing the band about the end of the shoe and for controlling the clamping pressure 65 comprising a cam mounted for movement

lengthwise of the shoe with said plunger, said cam having a portion inclined to the direction of movement of the plunger for closing the band during a portion of the operative movement of the wipers and another portion substantially parallel to said direction of movement for maintaining the band in closed position during further movement of the wipers. 70

16. In a machine of the class described, the combination with shoe positioning means, of end embracing wipers, manual means for reciprocating said wipers over an end of the shoe, a band for embracing and clamping the upper about the end of the shoe, 80 and operating and controlling means for said band comprising a cam arranged to be reciprocated by said wiper operating means and constructed to close the band during a portion of the advancing movement of the 85 wipers and then to maintain the clamping pressure of the band substantially unchanged as the wipers are advanced and retracted between predetermined limits over the shoe bottom. 90

17. In a machine of the class described, the combination with shoe positioning means, of end embracing wipers, manual means for advancing and closing said wipers over an end of the shoe, a band for embracing and clamping the upper about the end of the shoe, and operating and controlling means for said band comprising a cam mounted for reciprocatory movement and arranged to be operated by said manual means, said 100 cam having a portion extending substantially parallel to its direction of movement for maintaining the band in pressure applying relation to the shoe without substantial resistance to the movement of the wipers over the shoe. 105

18. In a machine of the class described, the combination with shoe positioning means, of end embracing wipers, operating means for advancing and retracting said wipers 110 over an end of the shoe, a band for embracing and clamping the upper about the end of the shoe, and operating means for said band comprising a path cam mounted for reciprocatory movement with the wipers 115 for closing and opening the band at the opposite sides of the shoe in predetermined relation to the wiper movements.

19. In a machine of the class described, the combination with shoe positioning means, 120 of end embracing wipers, operating means for advancing and closing said wipers over an end of the shoe, a band for embracing and clamping the upper about the end of the shoe, and operating means for said band 125 comprising a cam movable lengthwise of the shoe with the wipers and a bell crank connected to the band and arranged to be operated by said cam.

20. In a machine of the class described, the 130

- combination with shoe positioning means, of end embracing wipers, operating means for advancing and closing said wipers over an end of the shoe, a band for embracing and clamping the upper about the end of the shoe, a cam mounted for reciprocatory movement with the wipers, a bell crank arranged to be operated by said cam, and yielding connections between said bell crank and the band for closing the band about the end of the shoe.
21. In a machine of the class described, the combination with shoe positioning means, of end embracing wipers, a hand lever for advancing and closing said wipers over an end of the shoe, a band for embracing and clamping the upper about the end of the shoe, and mechanism operated by said hand lever for closing the band about the end of the shoe comprising spring means movable lengthwise of the shoe for applying yielding clamping pressure to the shoe through the band, said spring means being adjustable for varying the clamping pressure without affecting the relation between the band and the wiper operating means.
22. In a machine of the class described, the combination with shoe positioning means, of end embracing wipers, means for operating said wipers, an end embracing band, a band closing slide, a member connected to the wiper operating means for imparting movement to said slide, a compression spring between said member and slide, and means for adjusting the compression of said spring without affecting the relation between the member and the slide.
23. In a machine of the class described, the combination with shoe positioning means, of end embracing wipers, means for operating said wipers, an end embracing band, a cam arranged to be reciprocated by said wiper operating means, a yielding spring connection between said cam and the band for applying clamping pressure yieldingly to the shoe through the band, and means for adjusting said spring connection to vary the pressure applied.
24. In a machine of the class described, the combination with shoe positioning means, of a band for embracing an end of the shoe, band closing members movable lengthwise of the shoe at its opposite sides to close the band about the end of the shoe, means for wedging said members inwardly toward the sides of the shoe in their movement lengthwise of the shoe, and connections between said members and the ends of the band constructed to apply the force of said members unyieldingly to the band in the direction of the length of the shoe and to permit a relative adjustment lengthwise of the shoe between the members and the ends of the band.
25. In a machine of the class described, the combination with shoe positioning means, of a band for embracing an end of the shoe, band closing members movable lengthwise of the shoe at its opposite sides to close the band about the end of the shoe, said members being unyieldingly connected to the ends of the band in respect to movement lengthwise of the shoe, means for wedging said members inwardly toward the sides of the shoe in their movement lengthwise of the shoe, and means for effecting a relative adjustment lengthwise of the shoe between each end of the band and its connected closing member independently.
26. In a machine of the class described, the combination with shoe positioning means, of a band for embracing an end of the shoe, band closing members movable lengthwise of the shoe at its opposite sides to close the band about the end of the shoe, means for wedging said members inwardly toward the sides of the shoe in their movement lengthwise of the shoe, and unyielding connections between said members and the ends of the band constructed to permit relative adjustment between the members and the ends of the band both lengthwise and laterally of the shoe.
27. In a machine of the class described, the combination with shoe positioning means, of a band for embracing an end of the shoe, members movable lengthwise of the shoe at its opposite sides for closing the band about the end of the shoe, means for wedging said members inwardly toward the sides of the shoe in their movement lengthwise of the shoe, and connecting arms extending across from said members to the ends of the band, said arms being rigid with the members against the force applied by said members lengthwise of the shoe, and means for swinging said arms to adjust the ends of the band lengthwise of the shoe.
28. In a machine of the class described, the combination with shoe positioning means, of a band for embracing an end of the shoe, members movable lengthwise of the shoe at its opposite sides for closing the band about the end of the shoe, means for wedging said members inwardly toward the sides of the shoe in their movement lengthwise of the shoe, arms connected to the ends of the band and rigidly mounted on said closing members, and means for adjusting said arms relatively to the closing members both lengthwise and laterally of the shoe.
29. In a machine of the class described, the combination with shoe positioning means, of end embracing wipers, means for operating said wipers, and end embracing band, band closing members movable lengthwise of the shoe at its opposite sides, connections between said members and the ends of the band constructed to apply the force of said members unyieldingly to the band in the di- 120 125 130 135 140 145 150 155 160 165 170 175 180

rection of the length of the shoe, and operating mechanism for said band closing members comprising a cam mounted for reciprocatory movement with the wipers and constructed to apply the same predetermined band closing pressure to said members for different extents of wiper movement.

In testimony whereof I, the said JOSEPH

FAUSSE, have signed my name to this specification.

JOSEPH FAUSSE.

In testimony whereof I, the said RENÉ E. DUPLESSIS, have signed my name to this specification.

RENÉ E. DUPLESSIS.
